ASH TRAY

Anthony Redmond-Farrance, 69 Haverhill Road,
London, England

Filed Feb. 13, 1958, Ser. No. 49,655

Claims priority, application Great Britain Aug. 16, 1957

Term of patent 14 years

(Cl. D85—2)

I claim:

The ornamental design for an ash tray, as shown.
